(57) **CLAIM**

The ornamental design for a cable connector, as shown and
described.

DESCRIPTION

FIG. 1 is a front perspective view of a cable connector
according to the present invention;

FIG. 2 is a rear perspective view of the cable connector;

FIG. 3 is a top view of the cable connector;

FIG. 4 is a front view of the cable connector;

FIG. 5 is a bottom view of the cable connector;

FIG. 6 is a rear view of the cable connector;

FIG. 7 is a left side view of the cable connector; and,

FIG. 8 is a right side view of the cable connector.

The broken lines shown in FIGS. 1 through 8 represent
portions of the cable connector that form no part of the
claimed design.
